UNITED STATES PATENT OFFICE.

DANIEL CEDERBERG, OF LEOMINSTER, MASSACHUSETTS.

JOINER.

SPECIFICATION forming part of Letters Patent No. 653,616, dated July 10, 1900.

Application filed March 3, 1900. Serial No. 7,205. (No model.)

To all whom it may concern:

Be it known that I, DANIEL CEDERBERG, a citizen of Sweden, residing at No. 292 West street, Leominster, in the county of Worcester and State of Massachusetts, have invented 5 new and useful Improvements in Joiners, of which the following is a specification.

This invention relates to improvements in woodworking machinery of the class generally termed "joiners" for the purpose of planing the edges of boards preparatory to matching or making glue-joints for the same, and it is carried out as follows, reference being had to the accompanying drawings, where- 15 in—

Figure 1 represents a rear view of the improved machine. Fig. 2 represents an end view seen from X in Fig. 1. Fig. 3 represents a top plan view of Fig. 1. Fig. 4 represents a 20 front view of the machine, and Fig. 5 represents a top plan view of the rotary planing-tool.

Similar letters refer to similar parts wherever they occur on the different parts of the 25 drawings.

In the drawings, A represents the base portion of the frame of the machine, having made integral with it a horizontal table-top B, provided on its upper side with a preferably V-shaped guide-rib C and a preferably flat guide rib or way D, on which the carrier E is longitudinally movable, as will herein-after be more fully described.

The carrier E is provided on its under side 35 with a longitudinal groove e, adapted to receive the guide-rib C on the table-top B, as shown in Fig. 2. The carrier E is provided at its ends with upwardly-projecting brackets E' E', to the upper ends of which is se- 40 cured or made integral therewith a bar or beam E'', through screw-threaded perforations in which are screwed the adjustable clamping-screws F F F, as shown in the drawings.

45 f f f are hand wheels or cranks secured to the upper ends of the screws F F F, as shown.

G G are the boards, which are placed on the carrier E and secured firmly in position thereon by means of the clamping-screws F F, as 50 shown.

In the upper portion of the bar or beam E'' is made a longitudinal groove e', adapted to

receive an upper guide-rib a', secured to or made integral with an overhanging arm on the upper ends of vertical uprights extending above the table of the machine-frame, as shown.

In bearings in the frame is journaled the rotary vertical shaft h, to which is secured 60 the knife-carrying block H, having secured to two of its opposite sides the knives or planer-blades H' H', as shown in the drawings. To the lower end of the shaft h is secured a pulley h', to which a rotary motion is imparted by means of a belt I, leading from 65 a pulley K, secured to a driving-shaft k, as shown in Fig. 1. In practice I prefer to secure to said driving-shaft k a small pulley l, from which leads a belt L to an overhead pulley L', secured to a shaft m, having secured 70 to it a pulley M, from which leads a belt N to a pulley n, secured to a shaft O, suitably journaled in bearings, as shown in Fig. 1.

In stationary bearings below the table-top B is journaled a screw-shaft P, working in a 75 screw-threaded lug E³, secured to the under side of the carrier E, as shown in Fig. 1.

In practice I impart a reciprocating motion to the carrier E and the boards G held thereon by means of a pulley O', secured to the 80 shaft O, and direct and cross belts O'' O³, leading from said pulley O' to pulleys on the screw-shaft P, as is common in belt transmission for reciprocating a carrier and need not be referred to in detail.

85 Q is a vertical guide-plate adjustably secured to the table-top B, and it serves as a guide against the edges of the boards G preparatory to being acted on by the rotary cutters H' H' after said boards have been 90 clamped in position on the carrier E.

In practice I prefer to secure to the table-top B on the opposite side of the rotary cutter a vertical guide-plate R, against which the edges of the boards are guided after being squared by the rotary cutters.

95 The operation of the machine is as follows: The boards to be squared on their edges are placed one on the top of the other on the carrier E, with their edges against the guide Q, 100 after which they are clamped and secured in position on said carrier by means of the clamping-screws F F, as hereinabove described. The machine is then set in opera-

tion, causing the cutter-shaft *h*, with its cutter-blades, to rotate and the carrier *E* and boards held thereon to move in the direction of the arrow shown in Fig. 1, and in so doing 5 the rotary cutter-blades *H*' *H*' are brought in contact with the edges of the boards, causing them to be squared suitable for matching or making glue-joints, as may be desired. After the entire lengths of the boards have 10 traveled by the rotary cutter and been shaped and squared the motion of the carrier and boards attached to it is reversed, either by hand or any well-known automatic shipper device, so as to return the carrier to its original position, after which the boards are 15 released and reversed in position on the carrier and the operation repeated for squaring the opposite edges of the boards, and so on during the operation of squaring successive 20 boards for the purpose stated.

What I wish to secure by Letters Patent and claim is—

The herein-described joiner, consisting in

combination, of a frame having a table provided with horizontal guides, standards rising above the table and provided with an overhanging arm having a guide thereon, a vertical cutting-knife journaled in the frame and with its operating-cutters above the table, a carrier provided with guideways in its top and bottom to coöperate with the guides on the table and the overhanging arm of the frame, clamping-screws arranged in the top of said carrier and adapted to clamp a series of boards in the carrier, and means for causing said carrier and the boards clamped therein to travel in front of the cutting-knife, substantially as described. 25 30 35

In testimony whereof I have hereunto set my hand in presence of two subscribing witnesses. 40

DANIEL CEDERBERG.
